UNITED STATES PATENT OFFICE.

DANIEL L. CHANDLER, OF FITCHBURG, MASSACHUSETTS, ASSIGNOR, BY MESNE ASSIGNMENTS, TO VEND ADS CORP., A CORPORATION OF MASSACHUSETTS.

VENDING MACHINE.

Application filed January 10, 1921. Serial No. 436,103.

To all whom it may concern:

Be it known that I, DANIEL L. CHANDLER, a citizen of the United States, residing at Fitchburg, in the county of Worcester and State of Massachusetts, have invented new and useful Improvements in Vending Machines, of which the following is a specification.

This invention relates to a machine for vending articles of the character in which manually operable mechanism is provided which is rendered operable by means of a coin inserted in the casing of the machine.

The object of the invention is to provide a simple and effective slot machine for vending articles which will operate when a coin is deposited therein to deliver one of the articles to the party depositing the coin, but which in case there are none of such articles in the machine, will eject the coin from the machine so that the party who has deposited the coin may obtain possession of his coin.

The machine of this invention also has for its object to provide a means for agitating the articles in the article receptacle so that they will feed readily to the delivery mechanism. Said machine also has an attachment for operating an advertising device which will display a different card for each time that the machine is operated. The mechanism of this invention which feeds the article out of the machine and deposits the coin which has been placed in the machine in a coin receptacle while delivering the article to the party who has so deposited the coin, and the mechanism for operating the advertising device are substantially the same as the mechanism embodied by me in an application filed in the United States Patent Office on January 24th, 1920, Serial Number 353,712.

In the device of this invention the article which is to be vended renders the mechanism for ejecting the coin from the machine inoperative for that purpose, but when the articles are exhausted from the machine or do not feed to the delivery mechanism so as to be ejected from the machine, then said

mechanism is allowed to become operative to 50 eject the coin from the machine. If no coin is placed in the machine, then the manipulation of the lever whereby the article is ejected from the machine and the coin deposited in the coin receptacle becomes in- 55 operative.

The invention consists in a machine of the character set forth of mechanism which, upon the deposit of a coin in the machine is operable to eject the coin from the machine 60 when the article to be vended is not ejected therefrom, but which, when a coin is deposited in the machine and the machine ejects the article to be vended therefrom, will deposit the coin in a coin receptacle within 65 said machine.

The invention further consists in certain improved mechanisms for agitating the articles in the article receptacle and in the combination and arrangement of parts set 70 forth in the following specification and particularly pointed out in the claims.

Referring to the drawings:

Figure 1 is a front elevation of the machine.

Fig. 2 is a sectional plan taken on line 2-2, Fig. 1, with the parts illustrated in their relative locations when the machine is ready to be operated with an article ready to be vended and a coin in position to render 80 the article and coin feeding mechanism operable.

Fig. 3 is a sectional elevation taken on line 3-3, Fig. 2.

Fig. 4 is a sectional elevation taken on 85 line 4-4, Fig. 2 looking toward the right in said figure with the parts in the relative positions illustrated in Fig. 2.

Fig. 5 is a sectional elevation taken on the line 5-5, Fig. 2 looking toward the left in 90 said figure.

Fig. 6 is a sectional plan similar to Fig. 2 illustrating the relative positions of the parts when the machine has been operated with an article in position to be fed with a 95 coin in position to render the feeding mechanism operable and the article and coin have been fed part way forward in readiness, one

to be ejected from the machine and the other to be delivered to the coin receptacle inside the machine.

Figure 7 is a sectional plan similar to 5 Figs. 2 and 6 illustrating the parts in the relative positions assumed thereby when no article is being fed but with a coin in position to be ejected from the machine upon the completion of the forward movement of 10 the coin feeding and ejecting mechanism.

Fig. 8 is a detail plan view partly in section of the auxiliary chute and its carrier which ejects the coin from the machine.

Fig. 9 is a front elevation of the parts 15 illustrated in Fig. 8.

Fig. 10 is a detail sectional elevation illustrating the actuating member and a portion of the carrier slide locked together by means of a coin.

20 Fig. 11 is a detail side elevation of the holding slide.

Like numerals refer to like parts throughout the several views of the drawings.

In the drawings, 5 is the casing of the machine, 6 is a receptacle for the articles to be vended, 7 is that portion of the casing which encloses the advertising device. The casing 5 is provided with a cover 8 pivotally mounted at 9 to swing on said casing and provided 25 with a hasp 10 which engages a staple 11 to which it is locked by a padlock 12. A receptacle 13 for coins consists of a drawer which is slidable in the casing 5 and is locked in position in said casing by a pin 14 30 slidable vertically in the casing 5 and having its lower end adapted to project into a notch 15 in the coin receptacle 13. The upper end of the pin 14 when the cover is closed is adjacent to the underside thereof so that 35 said locking pin cannot be moved out of engagement with the coin receptacle until the cover 8 is swung out of alignment therewith and this cannot be done until the cover 8 is unlocked. The article receptacle 6 in 40 this embodiment of my invention preferably consists of a glass cylinder 16 which is secured to a base 17 by a rim 18 and by rods 19. A cover 20 is hinged at 21 to the rim 18 and is locked thereto by a hasp 22 and padlock 23, see Figure 1. The base 17 of the article 45 receptacle is conical in form at 23' and has a cylindrical chute 24 extending downwardly from the bottom thereof which terminates inside the casing and acts as a guide to feed 50 the articles to be vended from the article receptacle to the mechanism by which said articles are fed out of the machine. Said chute is provided with an annular flange 25 and is fastened by screws 26 to the top of the 55 casing 5. A carrier slide 27 is mounted to slide in ways 28 and 29 provided in the casing 5 and said carrier slide is adapted to be reciprocated forwardly and backwardly beneath the chute 24 and the column of articles 60 30 contained therein. Said carrier slide is

provided with an orifice 31 which extends therethrough and is large enough to admit the lowermost article 30' of said column of articles when the carrier slide is in its rearward or starting position, see Figures 2, 3 70 and 4. A reciprocatory motion is imparted to said carrier slide to carry the lowermost article 30' of said column of articles forward along the upper face of a horizontal partition 32 which extends across the casing, and 75 said casing is also provided with a chute 33, the inlet opening 34 of which is located immediately below an opening 35 which extends through the partition 32, said openings 34 and 35 being located immediately in front 80 of the orifice 31. The chute 33 extends downwardly from its upper end and empties into a shelf 36 forming a part of the front of the casing 5. The carrier slide 27 has a right angled arm 37 which extends 85 downwardly from the back of said slide and then horizontally forward projecting through a hole 38 provided in the back of the chute 33 and forming a detent to prevent the articles which are being vended from being 90 delivered to the shelf 36 before the carrier slide is released and allowed to return to its initial position. A reciprocatory motion is imparted to the slide 27 by an actuating member which consists of a rod 39 slidably 95 mounted in the front of the casing at 40, and also slidably mounted at 41 in a vertical front plate 42 forming a part of the carrier slide 27. The rod 39 is reciprocated by means of a bell crank lever 43, one arm 44 of which is bifurcated at 45 and engages a cross pin 46 fast to the rod 39. The lever 43 is pivoted at 50 to the casing of the machine and has an arm 51 constituting a handle and provided with a thumb piece 52. This handle in the operation of the machine plays 100 downwardly and upwardly in a slot 53 provided in the front of the casing and is moved upwardly by springs 54, the upward motion of the handle 51 and the rearward motion 105 of the arm 44 and rod 39 being limited by the engagement of the arm 44 with the way 28, see Figure 5. The downward movement of the handle 51 and therefore the forward movement of the rod 39 are limited by the 110 engagement of said handle 51 with the bottom of the slot 53. The cover 8 is provided with a coin chute 55 which has a slot 56 therein to guide the coin which is put in the machine, and this slot terminates at its lower 115 end in alignment with a vertical slot 57 provided in the wall 42 of the carrier slide 27 and extending transversely of said slide and of said actuating member 39. When the carrier slide 27 is in its rearward position 120 as illustrated in Figures 2 and 4, the slot 57 is in alignment with the slot 56, and a notch 58 which is provided in the actuating member 39 is then in alignment with said slot 57. The notch 58 has a shoulder 59 sub- 125

stantially at right angles to the median longitudinal line of said actuating member and an inclined edge 60 extending forwardly from the shoulder 59 to the upper edge of 5 said actuating member. When the carrier slide is in its forward position the slot 57 is in alignment with an opening 61 provided in the horizontal partition 32 and above the coin receptacle 13.

10 By reference to Figures 2 and 5 it will be seen that the outer end of the coin slot 57 in the carrier slide or the right hand end of said slot as viewed in Figure 2 is closed and opened alternately by means of a holding slide 62 which is slidably mounted upon the carrier slide 27 and is adapted to slide in ways 63 provided thereon. This holding slide has a downwardly projecting arm 64, (Figures 5 and 11) which moves forwardly 15 and backwardly when the carrier slide is moved forwardly and backwardly and is adapted to engage, when the carrier slide nears the end of its forward movement, a stop 65, and when said carrier slide nears 20 the end of its rearward movement, said arm is adapted to engage a stop 66 and to thus alternately open the end of the slot 57 and allow the coin to pass out of said slot and into the coin receptacle 13, and to close said 25 slot to prevent the coin from passing out of said slot when it is necessary to hold the coin in said slot to lock the carrier slide and the actuating member together.

As will be seen by reference to Figures 35 2 and 4, a latch 66 is pivoted at 67 to the frame of the machine, said latch having an arm 68 provided with a series of teeth 69 on one edge thereof and another arm 70 which is normally held in contact with the 40 frame by a spring 71, one end of which is connected to the arm 70 and the other end to a pin 72 fast to the frame of the machine. When the carrier slide fails to feed an article to the exit chute 33, the coin 73 is 45 ejected from the machine by means of an auxiliary chute 74, see Figs. 2, 4, 5, 6, 7, 8 and 9, which, at its lower end opens into the chute 33. Said auxiliary chute is mounted upon a carrier frame 75 consisting of a 50 cross bar 76 and two rods 77 and 78 which are fastened thereto. The rod 77 is slidably in ears 79 and 80 fast to the frame of the machine, and is provided with a cross pin 81 which is normally held against the ear 55 79 by a spring 82 which encircles the rod 77 and bears at one end against the ear 80 and at other end against the cross pin 81. The rod 78 is slidably mounted in the vertical front plate 42 of the carrier slide 27 and is 60 also slidably mounted at its rear end in a vertical flange 83 which encircles the orifice 31 and forms a part of the carrier slide 27. A cam lever 84 is pivoted at 85 to an arm 86 which is fastened to the carrier slide 65 27. One arm 87 of said lever is bifurcated

at 88 and engages a vertical pin 89 which is fastened to the rod 78. Another arm 90 on said lever has a pin 91 extending upwardly therefrom at its free end and in the operation of the machine this pin is adapted to 70 engage the edge 92, or the edge 93 of a finger 94 on a stationary cam plate 95 for the purpose of assisting in the positioning of the auxiliary coin chute 74 as more fully 75 hereinafter described.

The articles in the receptacle 6 are agitated or stirred in order to assist in feeding them down the chute 24 by fingers 96 and 97 which are fast to levers 98 and 99 pivoted at 100 and 101, said levers having a rocking 80 motion imparted thereto by pins 102 and 103 which are fastened to ears 104 and 105 forming a part of the carrier slide 27, see Figures 3 and 4.

The mechanism for operating the advertising device is also operated from the carrier slide by a pin 106 which engages an arm 107 fast to the rock shaft 108, said rock shaft having a rocker arm 109 thereon which is connected by a link 110 to a pawl and ratchet mechanism which operates substantially the same as that shown and described in my said application for United States Letters Patent No. 353,712 and in this case 90 requires no detailed description.

In order to close the slot 56 in the coin chute 55 when the slot 57 in the carrier slide is out of alignment therewith a horizontal plate 111 is provided upon the upper end of the vertical front plate 42 on the carrier slide and extends rearwardly therefrom so that when the carrier slide is moved forwardly from the position illustrated in Figure 4, this plate will pass beneath the bottom end of the slot 56 and close said slot so that 105 no coins can enter the slot 57 until the carrier slide is moved backwardly to its rearward position.

The general operation of the mechanism hereinbefore specifically described is as follows:—Assuming the parts to be in the relative positions illustrated in Figures 1, 2, 4 and 5 and that one of the articles 30' is located in the orifice 31 in the carrier slide 27 and that a coin 73 has been dropped into the coin chute 55 and has passed down the slot 56 and into the slot 57 in the carrier slide. At this time the actuating member 39 is in its rearward position with the arm 44 resting against the way 28, being held in that position by the springs 54 with the slot 56 in alignment with the slot 57 and with the detent arm 37 in the position indicated in Figure 4. As soon as the coin enters the slot 57 it will pass downwardly in said slot and project into the notch 58 in front of the shoulder 59 on the actuating member 39. The arm 51 of the bell crank lever 43 is now pushed downwardly by means of the thumb piece 52 and against the action of the springs 110 115 120 125 130

54 whereupon the actuating member 39 will be moved forward by means of the pin 46 and the arm 44 of the lever 43. The actuating member 39 being locked to the carrier 5 slide by the coin 73, will cause said carrier slide to move forwardly with it and the article 30' will be moved by said carrier slide along the horizontal partition 32 until it arrives in alignment with the opening 35 in 10 said horizontal partition, whereupon it will drop through the inlet opening 34 into the chute 33 and will pass down in said chute until it rests upon the detent arm 37 which, at this time, has been moved forward into 15 the position illustrated in dotted lines, Figure 4. During this forward movement of the carrier slide, the following operations take place: The teeth 69 on the latch 66 successively engage said coin and prevent the carrier 20 slide from moving backwardly until it has moved forwardly to the full extent of its forward movement as illustrated in Figure 6, and the holding slide 62 will move forwardly with the carrier slide and hold the 25 coin in the slot 57 until just before the carrier slide gets to the end of its forward movement, whereupon the arm 64 on said holding slide will engage the stop 65 and further forward movement of said holding slide will 30 be arrested, while the carrier slide will move forward until the slot 57 is open, and at the last part of this forward movement of the carrier slide the edge of the coin will ride upon the inclined edge 69' which will 35 rock the latch 66 upon its pivot 67 against the action of the spring 71 and as soon as the holding slide has been moved out of alignment with the slot 57, the spring 71 will cause the arm 68 of the latch to move 40 toward the right, Figure 6, and eject the coin 73 from the slot 57 whereupon said coin will drop through the opening 61 in the horizontal partition 32 and will fall into the coin receptacle 13. During the first part of the 45 forward movement of the carrier slide the auxiliary chute 74, the cross bar 76 and the rods 77 and 78 will remain stationary but the pivot 85 of the lever 84 will be moved forwardly as the same is fast to the arm 86 which is fastened to the carrier slide 27 until 50 the rear end of the rod 78 engages the lowermost article 30' and forces it up against the rear wall of the orifice 31, then upon a further forward movement of the carrier 55 slide, the article 30' being locked between the rear wall of the orifice 31 and the rear end of the rod 78 will push said rod 78 forward and this will cause the cross bar 76, the auxiliary chute 74 and the rod 77 to be 60 moved forwardly, together with the lever 84 until the parts assume the relative positions illustrated in Figure 6, in which it will be noted that the auxiliary chute 74 is out of alignment with the slot 57 and the pin 91 on 65 the lever 84 has engaged the inclined edge 92 of the finger 94 on the cam plate 95, whereupon further forward movement of the carrier slide, in addition to moving the holding slide out of alignment with the coin slot 70 will move the auxiliary slide 74 forwardly and keep it out of alignment with the coin 73 so that said coin has a free pathway out of the slot 57 and into the opening 61, the coin being ejected from the slot 57 at the end of the forward movement of the carrier slide as hereinbefore set forth. Upon releasing the lever 51, the parts will return to the relative positions illustrated in Figure 2, and the detent arm 37 will be drawn backwardly, dropping the article 30' and 80 allowing it to roll down the chute 33 and on to the shelf 36 where it may be obtained by the party operating the machine. This is the sequence of operation which takes place when a coin has been placed in a machine and when the article 30' is in position to be fed forward by the carrier slide. Now assuming that the coin has been placed in the machine and that there is no article in the orifice 31 and that the machine is operated as before to move the carrier slide forwardly, since there is no article in the orifice 31 when the carrier slide is moved forwardly the rod 78 will slide into said orifice and the vertical partition 42 will 90 slide forwardly until it abuts against the rear face of the cross bar 76. At this time the auxiliary chute will be in alignment with the slot 57 and with the coin 73 as illustrated in Figure 7, and the pin 91 on the lever 84 will have passed over into engagement with the edge 93 of the cam plate. Further forward movement from this point will cause the holding slide to be moved out of alignment with the coin slot 57, but the auxiliary 95 coin chute will travel with the carrier slide and will remain in alignment with the coin slot 57 until the latch 66 operates as before to knock the coin out of the slot 57 but in this instance the coin will be ejected from 100 the slot 57 into the auxiliary chute 74 whereupon said coin will travel down the chute 74 and into the chute 33 and upon the lever 51 being released and the parts moved backwardly into the positions illustrated in Figure 2 the coin will slide down the chute 33 and onto the shelf 36 where it may be obtained by the operator of the machine. 105 During the forward and rearward movement of the carrier slide whenever there is a coin in the slot 57, the stirring fingers 96 and 97 will be operated by the levers 98 and 99 to agitate the articles in the article receptacle by the pins 102 and 103 on the carrier slide. 110 The rearward position of the actuating member 39 relatively to the carrier slide 27 is determined by the rear end of said actuating member 39 abutting against a flange 112 forming a part of the carrier slide 27, or 115 120 125 130

by the arm 44 of the lever 51 engaging the way 28. The extreme forward position of the actuating member 39 is determined by the arm 51 of the lever 43 engaging the bottom of the slot 53 in the frame.

I claim:

1. A machine for vending articles having, in combination, a receptacle for articles, mechanism including a slide adapted to receive an article from said receptacle and feed said article out of said machine, said mechanism being rendered effective to feed said article out of said machine by the deposit of a coin therein, and mechanism adapted to eject said coin from said machine in the event no article is received by said slide from said receptacle.

2. A vending machine having, in combination, a receptacle for articles, mechanism adapted to receive an article from said receptacle and feed said article out of said machine, said mechanism being rendered effective to feed said article out of said machine by the deposit of a coin therein, and mechanism adapted to eject said coin from said machine in the event of said article feeding mechanism failing to feed an article as set forth, said coin ejecting mechanism being rendered ineffective to eject said coin from said machine by one of said articles while being fed by said article feeding mechanism.

3. A vending machine having, in combination, a receptacle for articles, mechanism adapted to receive an article from said receptacle and feed said article out of said machine, said mechanism being rendered effective to feed said article out of said machine by the deposit of a coin therein, and mechanism including a chute and adapted to eject said coin from said machine in the event of said article feeding mechanism failing to feed an article as set forth, said coin ejecting mechanism being rendered ineffective to eject said coin from said machine by one of said articles while being fed by said article feeding mechanism.

4. A vending machine having, in combination, a receptacle for articles, an outlet chute leading out of said machine, a slide with an orifice therein adapted to receive an article from said receptacle and conduct it to said chute, said slide having a slot therein adapted to receive a coin, an actuating member adapted to be locked to said slide by a coin in said slot, an auxiliary chute adapted to guide a coin out of said machine and mechanism rendered ineffective by one of said articles while being fed by said slide to said outlet chute to position said auxiliary chute to receive said coin from said slide.

5. A vending machine having, in combination, a receptacle for articles, an outlet chute leading out of said machine, a slide with an orifice therein adapted to receive an article from said receptacle and conduct it

to said chute, said slide having a slot therein adapted to receive a coin, an actuating member adapted to be locked to said slide by a coin in said slot, an auxiliary chute adapted to guide a coin out of said machine and mechanism rendered ineffective by one of said articles while being fed by said slide to said outlet chute to position said auxiliary chute to receive said coin from said slide, said last named mechanism being rendered effective to position said auxiliary chute to receive said coin from said slide by the failure of said slide to receive one of said articles.

6. A vending machine having, in combination, a receptacle for articles, an outlet chute leading out of said machine, a slide with an orifice therein located beneath said receptacle and adapted to receive an article in said orifice from said receptacle and conduct it to said outlet chute, said slide having a slot therein adapted to receive a coin, an actuating member adapted to be locked to said slide by a coin in said slot, an auxiliary chute adapted to guide a coin out of said machine, a slidably mounted carrier frame to which said auxiliary chute is attached adapted to project into said orifice and contact with one of said articles located therein, and mechanism rendered ineffective by said article while being fed by said carrier slide to said outlet chute to position said auxiliary chute to receive said coin from said slide.

7. A vending machine having, in combination, a receptacle for articles, an outlet chute leading out of said machine, a slide with an orifice therein located beneath said receptacle and adapted to receive an article in said orifice from said receptacle and conduct it to said outlet chute, said slide having a slot therein adapted to receive a coin, an actuating member adapted to be locked to said slide by a coin in said slot, an auxiliary chute adapted to guide a coin out of said machine, a slidably mounted carrier frame to which said auxiliary chute is attached adapted to project into said orifice and contact with one of said articles located therein, and mechanism rendered ineffective by said article while being fed by said carrier slide to said outlet chute to position said auxiliary chute to receive said coin from said slide, said last named mechanism being rendered effective to position said auxiliary chute to receive said coin from said slide by the failure of said slide to receive one of said articles.

8. A vending machine having, in combination, a receptacle for articles, an outlet chute leading out of said machine, a slide with an orifice therein adapted to receive an article from said receptacle and convey it to said outlet chute, said slide having a slot therein adapted to receive a coin, an

actuating member adapted to be locked to said slide by a coin in said slot, an auxiliary chute adapted to guide a coin out of said machine, said auxiliary chute being normally out of alignment with said slot, a slidably mounted carrier frame to which said auxiliary chute is attached, a portion of said carrier frame being adapted to project into said orifice when said carrier slide 10 is moved forwardly, and mechanism adapted to move said auxiliary chute into alignment with said slot during the forward movement of said carrier slide, said last named mechanism being rendered ineffective by one of said articles when located in said orifice.

9. A vending machine having, in combination, a receptacle for articles, an outlet chute leading out of said machine, a slide 20 with an orifice therein adapted to receive an article from said receptacle and convey it to said outlet chute, said slide having a slot therein adapted to receive a coin, an actuating member adapted to be locked to said slide by a coin in said slot, an auxiliary chute adapted to guide a coin out of said machine, said auxiliary chute being normally out of alignment with said slot, a slidably mounted carrier frame to which said auxiliary chute 25 is attached, a portion of said carrier frame being adapted to project into said orifice when said carrier slide is moved forwardly, a lever pivoted to said slide and connected to said carrier frame and a stationary cam 30 plate adapted to be engaged by said lever during the forward movement of said carrier slide, whereby when said portion of said carrier frame engages an article in said orifice, said auxiliary frame will be held out of alignment with said slot during the forward movement of said carrier slide.

10. A vending machine having, in combination, a receptacle for articles, an outlet chute leading out of said machine, a slide 45 with an orifice therein adapted to receive an article from said receptacle and convey it to said outlet chute, said slide having a slot therein adapted to receive a coin, an actuating member adapted to be locked to said slide by a coin in said slot, an auxiliary chute adapted to guide a coin out of said machine, said auxiliary chute being normally out of alignment with said slot, a slidably mounted carrier frame to 50 which said auxiliary chute is attached, a portion of said carrier frame being adapted to project into said orifice when said carrier slide is moved forwardly, a lever pivoted to said slide and connected to said carrier frame and a stationary cam plate adapted to be engaged by said lever during the forward movement of said carrier slide, whereby when said portion of said carrier frame engages an article in said orifice, said auxiliary frame will be held out of align-

ment with said slot during the forward movement of said carrier slide, and whereby when said portion of said carrier frame does not engage an article in said orifice, said auxiliary chute will be positioned in alignment with said slot during the forward movement of said carrier slide. 70

11. A machine for vending articles having, in combination, a receptacle for articles, mechanism including a slide adapted to receive an article from said receptacle and feed said article out of said machine, said mechanism being rendered effective to feed said article out of said machine by the deposit of a coin therein, means associated with 80 said article receiving mechanism and adapted to agitate said articles to facilitate the feeding thereof from said receptacle to said article receiving and feeding mechanism, and mechanism adapted to eject said coin 85 from said machine in the event no article is received by said slide from said receptacle. 90

12. A machine for vending articles having, in combination, a receptacle for articles, a receptacle for coin, an outlet chute leading out of said machine, a slide with an orifice therein adapted to receive an article from said receptacle and convey it to said outlet chute, said slide having a slot therein adapted to receive a coin, an actuating member 95 adapted to be locked to said slide by a coin in said slot, mechanism adapted to eject said coin from said slot and into said coin receptacle, and mechanism rendered effective by the absence of an article in said orifice 100 to eject said coin from said machine. 95

13. A machine for vending articles having, in combination, a receptacle for articles, a carrier slide located beneath said receptacle and having an orifice therein adapted 105 to receive one of said articles, a chute leading out of said machine, means adapted to be locked to said carrier by a coin whereby said slide may be moved to bring said orifice out of alignment with said receptacle and 110 into alignment with said chute to allow one of said articles to pass into said chute and out of said machine, and mechanism adapted to eject said coin from said machine in the event of said carrier slide failing to feed 115 an article as set forth. 115

14. A vending machine having, in combination, a casing, a receptacle adapted to contain articles, a carrier slide movable beneath said receptacle and adapted to receive one of said articles, an outlet chute provided in said casing having an inlet opening beneath the path of travel of said slide and an outlet opening extending outside said casing, a manually operable actuating member slidable in said casing and in said slide, said slide being provided with a vertical slot extending transversely of said actuating member, and said actuating member being provided with a notch adapted to be brought 120 125 130

into and out of alignment with said slot, whereby upon the introduction of a coin into said slot, said slide may be locked to said actuating member and mechanism 5 adapted to eject said coin from said machine when said actuating member has been operated in the event of said slide failing to receive an article from said receptacle.

15. A vending machine having, in combination, a casing, a receptacle adapted to contain articles, a carrier slide movable beneath said receptacle and adapted to receive one of said articles, an outlet chute provided in said casing having an inlet opening 10 beneath the path of travel of said slide and an outlet opening extending outside said casing, a manually operable actuating member slideable in said casing and in said slide, said slide being provided with a vertical slot extending transversely of said actuating member, and said actuating member being provided with a notch adapted to be brought into and out of alignment with said slot, whereby upon the introduction of a 15 coin into said slot, said slide may be locked to said actuating member, means to lock said coin in said slot in engagement with said notch and mechanism adapted to eject said coin from said machine when said actuating member has been operated in the event of 20 said slide failing to receive an article from said receptacle.

16. A vending machine having, in combination, a casing, a receptacle adapted to contain articles, a carrier slide movable beneath said receptacle and adapted to receive one of said articles, an outlet chute provided in said casing having an inlet opening beneath the path of travel of said slide and an 25 outlet opening extending outside said casing, a manually operable actuating member slideable in said casing and in said slide, said slide being provided with a vertical slot extending transversely of said actuating member, and said actuating member being provided with a notch adapted to be brought into and out of alignment with said slot, means extending across said slot and adapted to hold a coin in said slot and in engagement with said notch, whereby said slide and actuating member may be locked together, and mechanism adapted to eject said coin from said machine in the event of 30 said slide failing to receive an article from said receptacle.

17. A vending machine having, in combination, a casing, a receptacle adapted to contain articles, a carrier slide movable beneath said receptacle and adapted to receive one 35 of said articles, an outlet chute provided in said casing having an inlet opening beneath the path of travel of said slide and an outlet opening extending outside said casing, a manually operable actuating member slideable in said casing and in said slide, said

slide being provided with a vertical slot extending transversely of said actuating member, and said actuating member being provided with a notch adapted to be brought into and out of alignment with said slot, holding means extending across said slot and adapted to hold the coin in said slot and in engagement with said notch, means to move said holding means out of alignment with said slot at the end of the forward movement of said slide and to move said holding means into alignment with said slot during the backward movement of said slide and mechanism adapted to eject said coin from said machine in the event of said carrier slide failing to receive an article from said receptacle. 70

18. A vending machine having, in combination, a casing, a receptacle adapted to contain articles, a carrier slide movable beneath said receptacle and adapted to receive one of said articles, an outlet chute provided in said casing having an inlet opening beneath the path of travel of said slide and an outlet opening extending outside said casing, a manually operable actuating member slideable in said casing and in said slide, said slide being provided with a vertical slot extending transversely of said actuating member, and said actuating member being provided with a notch adapted to be brought into and out of alignment with said slot, holding means mounted on said slide movable relatively thereto and adapted to extend across said slot and hold said coin in said slot and in engagement with said notch, whereby upon the introduction of a coin in said slot, said slide and actuating member may be locked together, means to move said holding means out of alignment with said slot during the forward movement of said carrier slide and into alignment with said slot during the rearward movement of said carrier slide and mechanism adapted to eject said coin from said machine in the event of said carrier slide failing to receive an article from said receptacle. 90

19. A vending machine having, in combination, a casing, a receptacle adapted to contain articles, a carrier slide movable beneath said receptacle and adapted to receive one of said articles, an outlet chute provided in said casing having an inlet opening beneath the path of travel of said slide and an outlet opening extending outside said casing, a manually operable actuating member slideable in said casing and in said slide, said slide being provided with a vertical slot extending transversely of said actuating member, and said actuating member being provided with a notch adapted to be brought into and out of alignment with said slot, and a holding slide mounted upon said carrier slide and adapted to extend across said slot whereby upon the introduction of a coin into 110

5 said slot said carrier slide and actuating member may be locked together, means to move said holding slide out of alignment with said slot during the forward movement of said carrier slide, said means being adapted to move said holding slide into alignment with said slot during the rearward movement of said carrier slide, and mechanism adapted to eject said coin from said machine 10 in the event of said carrier slide failing to receive an article from said receptacle.

20. A vending machine having, in combination, a casing, a receptacle adapted to contain articles, a carrier slide movable beneath said receptacle and adapted to receive one of said articles, an outlet chute provided in said casing having an inlet opening beneath the path of travel of said slide and an outlet opening extending outside said casing, a 25 manually operable actuating member slid- able in said casing and in said slide, said slide being provided with a vertical slot extending transversely of said actuating member, and said actuating member being provided with a notch adapted to be brought into and out of alignment with said slot, whereby upon the introduction of a coin into said slot, said slide may be locked to said actuating member, means to limit the distance 30 to which said actuating member can slide in said carrier slide, and mechanism adapted to eject said coin from said machine in the event of said carrier slide failing to feed an article when a reciprocatory motion is im- 35 parted to said slide.

21. A vending machine having, in combination, a casing, a receptacle adapted to contain articles, a carrier slide movable beneath said receptacle and adapted to receive one of said articles, an outlet chute provided in said casing having an inlet opening beneath the path of travel of said slide and an outlet opening extending outside said casing, a 40 manually operable actuating member slid- able in said casing and in said slide, said slide being provided with a vertical slot extending transversely of said actuating member, and said actuating member being provided with a notch adapted to be brought into and out of alignment with said slot, whereby upon the introduction of a coin into said slot, said slide may be locked to said actuating member, said casing being provided with a slot adapted to 45 align with the slot in said carrier slide when said carrier slide is in its rearward position, means on said carrier slide adapted to close the slot in said casing when the slot in said carrier slide is out of engagement there- 50 with and mechanism adapted to eject said coin from said machine in the event of said carrier slide failing to receive and feed an article to said outlet chute when moved by said actuating member.

65 22. A vending machine having, in combi-

nation, a casing, a receptacle adapted to contain articles, a carrier slide movable beneath said receptacle and adapted to receive one of said articles, an outlet chute provided in said casing having an inlet opening beneath the path of travel of said slide and an outlet opening extending outside said casing, a manually operable actuating member slid- able in said casing and in said slide, said slide being provided with a vertical slot ex- 70 tending transversely of said actuating member, and said actuating member being pro- 75 vided with a notch adapted to be brought into and out of alignment with said slot, said notch terminating at its rear end in a shoulder and being bevelled forwardly from said shoulder, whereby said actuating member will be locked by a coin located in said slot to said carrier slide when said carrier slide is being moved forward, and said coin will be forced out of said slot during the rearward movement of said actuating member, and an auxiliary chute adapted to guide said coin into said outlet chute in the event of said carrier slide failing to feed an article into said outlet chute. 80

23. A vending machine having, in combination, a casing, a receptacle adapted to contain articles, a carrier slide movable beneath said receptacle and adapted to receive one of said articles, an outlet chute provided in said casing having an inlet opening beneath the path of travel of said slide and an outlet opening extending outside said casing, a 85 manually operable actuating member slid- able in said casing and in said slide, said slide being provided with a vertical slot ex- 90 tending transversely of said actuating member, and said actuating member being pro- 95 vided with a notch adapted to be brought into and out of alignment with said slot, said notch terminating at its rear end in a shoulder and being bevelled forwardly from said shoulder, whereby said actuating member will be locked by a coin located in said slot to said carrier slide when said carrier slide is being moved forward, and said coin will be forced out of said slot during the rearward movement of said actuating member, means to limit the distance to which 100 said actuating member can be moved rear- 105 wardly in said carrier slide and an auxiliary chute adapted to guide said coin into said outlet chute in the event of said carrier slide failing to feed an article into said out- 110 let chute. 115

24. A vending machine having, in combination, a casing, a receptacle adapted to contain articles, a carrier slide movable beneath said receptacle and adapted to receive one of said articles therefrom, a manually operable actuating member slid- able in said casing and in said slide, said slide being provided with a vertical slot extending transversely of said actuating member and said actuating mem- 120 125 130

ber being provided with a notch adapted to be brought into and out of alignment with said slot, whereby upon the introduction of a coin into said slot, said slide may be locked 5 to said actuating member, means adapted to engage said coin during the forward movement of said slide to prevent said slide from being moved rearwardly and mechanism adapted to eject said coin from said machine in the event of said slide failing to receive an article from said receptacle.

25. A vending machine having, in combination, a casing, a receptacle adapted to contain articles, a carrier slide movable beneath said receptacle and adapted to receive one of said articles therefrom, a manually operable actuating member slidable in said casing and in said slide, said slide being provided with a vertical slot extending transversely of said actuating member and said actuating member being provided with a notch adapted to be brought into and out of alignment with said slot, whereby upon the introduction of a coin into said slot, said 20 slide may be locked to said actuating member, means to lock said coin in said slot in engagement with said notch, means adapted to engage said coin during the forward movement of said slide to prevent said slide from being moved rearwardly and mechanism adapted to eject said coin from said machine in the event of said slide failing to receive one of said articles.

26. A vending machine having, in combination, a casing, a receptacle adapted to contain articles, a carrier slide movable beneath said receptacle and adapted to receive an article therefrom and rendered operable by the insertion of a coin therein to carry said article and eject it from said slide without contacting with said coin, means adapted to engage said coin during the forward movement of said slide to prevent said slide from being moved rearwardly and mechanism adapted to eject said coin from said machine in the event of said slide failing to receive one of said articles.

27. A vending machine having, in combination, a casing, a receptacle adapted to contain articles, a carrier slide movable be-

neath said receptacle and adapted to receive an article therefrom and rendered operable by the insertion of a coin therein to carry said article and eject it from said slide without contacting with said coin, a member having a series of teeth adapted to engage said coin during the forward movement of said slide to prevent said slide from being moved rearwardly and mechanism adapted to eject said coin from said machine in the event of said slide failing to receive one of said articles.

28. A vending machine having, in combination, a casing, a receptacle adapted to contain articles, a carrier slide movable beneath said receptacle and adapted to receive an article therefrom and rendered operable by the insertion of a coin therein, a pivoted member having a series of teeth adapted to engage said coin during the forward movement of said slide to prevent said slide from being moved rearwardly and mechanism adapted to eject said coin from said machine in the event of said carrier slide failing to receive one of said articles.

29. A vending machine having, in combination, a casing, a receptacle adapted to contain articles, a carrier slide movable beneath said receptacle adapted to receive one of said articles, and rendered operable by the insertion of a coin therein, an outlet chute in said casing having an inlet opening beneath the path of travel of said slide and an outlet opening extending outside said casing, a detent fast to said slide extending into said outlet chute and adapted to be operated by said slide to alternately stop and release one of said articles as it passes down said chute and mechanism adapted to eject said coin from said machine in the event of said carrier slide failing to receive one of said articles.

In testimony whereof I have hereunto set my hand in presence of two subscribing witnesses.

DANIEL L. CHANDLER.
